UNITED STATES PATENT OFFICE

JACOB L. SHERRICK, OF SCOTTDALE, PENNSYLVANIA

DUPLICATOR

Application filed July 27, 1931. Serial No. 553,285.

The invention relates to duplicators or hectographs employing the so-called gelatin copying or hectographing surfaces, usually consisting of a gelatin glycerine composition, although the invention is not limited to the use of any particular composition. It has for its objects, the provision of a construction which is relatively cheap so that the units may be discarded after the surface is worn out; which is very compact so that a large number of surfaces are available for use in an apparatus which occupies a limited space and is relatively light and easily handled; and in which the copying surfaces are protected from dirt and dust when the device is not in use. One embodiment of the invention is illustrated in the accompanying drawing, wherein:

Figure 1 is a plan view of one of the units. Fig. 2 is a section on the line II--II of Fig. 1. Fig. 3 is an enlarged section on the line III--III of Fig. 1. Fig. 4 is a section through one of the cover plates of the apparatus. Fig. 5 is a section on the line V--V of Fig. 4. And Fig. 6 is a section through a complete set made up of five units like that of Figs. 1 to 3 and two cover plates like that of Fig. 4.

Referring to the unit shown in Figs. 1 to 4, 1 is a plate preferably of fiber board, having 30 on each side around the edges the wood or fiber board strips 2, 2 and 3, 3, secured to the fiber board by any suitable means, such as cement or screws. Secured to each side of the plate by an adhesive inside the strips is a 35 sheet of hectographing material preferably a sheet of paper 4, water proofed with a pyroxylin plastic varnish and carrying a coating of hectographing composition 5, such composition being ordinarily of glycerine 40 and gelatin in the proportions of 8 to 1.

Extending through the edges of the plates are the pin and socket members 6, 6, 6, 6 each 45 consisting of a socket portion 6^a and a pin portion 7. These members serve as additional securing means for holding the strips 3, 3 to the edges of the fiber board 1. They also act as devices for positioning the units and releasably securing them together when 50 they are stacked to form a set as indicated in Fig. 6. The pins fit snugly enough in the

sockets so that the units are securely held together when not in use, but at the same time are readily separable. The pins are so arranged that the units fit together when turned end for end or upside down, thus facilitating 55 the assembly. Five units are shown in the set, but this may be varied to meet requirements.

When in assembled position, as shown, eight of the copying surfaces are protected 60 from dust and dirt by the assembly, leaving only the outer faces of the outer units unpro- 65 tected. To protect these faces, the cover plates 8, 8 of fiber board are employed (Figs. 4, 5 and 6). Each plate is provided with a border strip 9 around the edges. The plates are provided with pin and socket members 6 similar to the members 6 heretofore de- 70 scribed. These members 6 interfit with the pin and socket members carried by the outer units of the set, so that the covers are re- 75 leasably attached to the units in the same manner that the units are attached together.

The set of units is compact and easily as- 80 sembled and disassembled. When not in use, 75 all of the hectographing surfaces are protect- 85 ed from dust and injury. In case the hecto- graphing surfaces of a unit become worn out, it can be removed and a new unit substi- 90 tuted at a low cost, thus keeping the set in- 95 tact. The device presents a maximum hecto- graphing area in proportion to the space oc- 100 cupied and the cost as compared with the flat type of hectographing apparatus as heretofore constructed, this being due in a large measure to the use of the fiber board as a sup- port for the copying surfaces, and to the fact that one board acts as a base or support for two copying surfaces.

What I claim is:

1. In combination, a duplicator unit com- 90 prising a rectangular plate having a raised border portion on each side around the four edges of the plate, and a sheet of copying ma- 95 terial attached to each side of the plate inside the border portion and consisting of flexible material coated with a layer of hectographing composition, a cover plate for one of the sides, and pin and socket connections between said border portion and the cover for securing 100 the cover removably in position.

2. In combination, a duplicator made up of a series of units of similar size and shape provided with interfitting pins and sockets in their side edges so that the units may be placed one on top of the other and releasably secured together by the frictional engagement of the interfitting pins and sockets, and removable cover plates for the outer faces of the two outer units, each of said units comprising a slate-like plate having a raised border around the edges on each side, and a sheet of flexible material covered with a hectograph composition secured on each side of the plate.
- 15 3. In combination, a duplicator made up of a series of units of similar size and shape provided with interfitting pins and sockets in their side edges so that the units may be placed one on top of the other and releasably secured together by the frictional engagement of the interfitting pins and sockets and removable cover plates for the outer faces of the two outer units having pin and socket connections with such outer units, each of said units comprising a slate-like plate having a raised border portion around the edges on each side, and a sheet of material covered with a hectograph composition secured on each side of the plate, the pin and socket equipment of the units being all the same so that the units may be secured to each other and to the cover plates regardless of their relative arrangement.
- 30 4. In combination, a duplicator made up of a series of units of similar size and shape adapted to be assembled one upon the other with their edges flush, each of said units comprising a slate-like plate having a raised border around all four edges on each side, a sheet of material covered with a hectograph composition secured on each side of the plate, and means for securing the units together comprising a plurality of members carried by the borders of each unit and each consisting of a socket with its end flush with one face of the border and a pin projecting from the other face of the border and having a diameter such that it will make a close fit in one of the sockets.
- 45 5. In combination, a duplicator made up of a series of units of similar size and shape adapted to be assembled one on top of the other with their edges flush, means for releasably locking the units together and holding them against relative movement edge-wise, cover plates for the two outer units, and means for securing the cover plates releasably in position, each of said units comprising a slate-like plate having a raised border portion around the edges on each side, and a sheet of material covered with a hectograph composition secured on each side of the plate.
- 60 6. In combination, a duplicator made up of a series of units of similar size and shape adapted to be assembled one on top of the

other with their edges flush, means for releasably locking each unit to the unit or units with which it contacts and holding them against relative movements edgewise, cover plates for two outer units, and means for securing the cover plates releasably in position, each of said units comprising a slate-like plate having a raised border portion around the edges on each side, and a sheet of material covered with a hectograph composition secured on each side of the plate.

In testimony whereof, I have hereunto subscribed my name this 23rd day of July, 1931.

J. L. SHERRICK.
